A. BUTTER

DIRECTION INDICATOR

Filed July 20, 1922

Patented July 3, 1923.

1,460,701

UNITED STATES PATENT OFFICE.

ADOLF BUTTER, OF CLIFTON, NEW YORK.

DIRECTION INDICATOR.

Application filed July 20, 1922. Serial No. 578,353.

To all whom it may concern:

Be it known that I, ADOLF BUTTER, a citizen of the United States, residing at Clifton, in the county of Richmond and State of New York, have invented certain new and useful Improvements in Direction Indicators, of which the following is a specification.

This invention relates to automobile signals and has for its main object, the provision of a device which telescopes inward or outward as occasion may require much after the fashion of a person's hand will in notifying cars following that a change of direction is to be made.

Another object is to provide a signal device which will automatically close an electrical circuit and illuminate a star at the outermost extremity of the device.

Still another object is to provide a signal which will telescope out of the way when the actuating pressure is released.

These and other objects will become apparent in the description below, in which characters of reference will refer to the like-named parts in the drawing.

Referring briefly to the drawing, Figure 1, represents a transverse sectional view of the device in extended position.

Figure 2 is a side elevation view showing the device in the telescoped position.

Figure 3 is an enlarged sectional view illustrating the method of automatically closing the circuit.

Figure 4 is an end elevational view of the sheave wheel with the cover plate.

Figure 5 is a cross-sectional view taken on the line 5—5 of Figure 1 and illustrates the method of an anchoring the current carrying wire to a shell.

Referring in detail to the drawing, the numeral 10 indicates the side wall of an automobile-body to the outside surface of which is secured by the bolts 11 an annular shell 12 which has an internal flange 13 formed to the other end. A smaller shell 15 having external 14, and internal flanges 16 formed thereto at its opposite ends is adapted to slide within the shell 12 and telescope into the chamber of the latter. Flange 13 of shell 12 and flange 14 of shell 15 form stop members and also contacters for closing an electrical circuit the construction of the latter will be more fully hereinafter described.

Similarly a shell 18 having an external flange 17, is adapted to telescope into the

chamber of the intermediate shell 15. At the outermost end of the shell 18 a socket 19 is located and has an annular casing 20 formed therewith in which is mounted at 60 the opposite edges convex lenses 22, the surfaces of said lenses having an outline of a star formed thereon by painting the background 22 black.

Separating wall 23 of the socket 19 has secured thereto an eye-bolt to which is attached one end of a thin wire cable 25 which traverses the several telescoping shells and passes thru the thimble 26 after which it follows a downward course and is secured to the periphery of the grooved sheave wheel 27.

An expansion coil spring 28 is adapted to urge the telescoping shells 12, 15 and 18, into extended position.

The socket 19 has secured thereto a dust tube 29 which has a tube 30 slidably mounted on its periphery the latter tube sliding into the fixed tube 31. It is apparent from Figure 1 that as the device is extended by the spring 28 or retracted, both the internal shells and the outside tube members will be simultaneously extended or retracted the tubes 29, 30 and 31 merely forming a dust cap for the device.

The sheave wheel 27 is preferably rotatably mounted on a stud secured to the automobile-body member 10. A handle 32 having a spring clip catch 33 secured thereto, is formed to the sheave wheel 27 and is provided for actuating the device.

Contact plates 36 and 36' separated by the gap 37 and insulated from body 10, and secured to the wall 10 of the latter are adapted to keep the entire device in open circuit, and retracted as illustrated in Figure 2. The handle will find itself in the end of the slot indicated at 35'.

A thin casing 34 is fitted over the sheave and all other exposed parts, and has a radial slot 35 therein in which the lower end of the handle 32 is engaged.

When handle spring clip 33 is depressed and disengaged from the notch at end 35' of the slot 35, the entire system of shells and tubes will be extended outwardly by the action of coil spring 28. As the handle arrives at the opposite end of slot 35, a contact plate 38 insulated from and secured to sheave wheel 27 directly beneath the handle bridges the gap 37 between contact plates 36 and 38 thereby closing the circuit in the wires 44.

and 45 energizing the line to the flange 13 of shell 12.

Electrical contact thru the several shells is made by the small bolts 40 secured to the 5 internal flanges 13, 16 and 14, 17, respectively, by, the threaded nuts 41. The bolts 40 are electrically insulated from the said flanges by the insulating collar 39. It is obvious from Figures 1 and 3, that, when the 10 tube device is extended each pair of bolts 40, being aligned with each other, will have their heads contact with each other, thereby closing the circuit through the shells simultaneously, as the same function takes 15 place simultaneously thruout the several shells, the wire 43 connecting each shell to the adjacent one.

It is readily apparent that as the device is 20 fully extended, a complete circuit is automatically made, and by which the filament lamp 46 is energized, thus giving a visible signal to vehicles in the rear of a change of direction.

Rotating the handle in the direction (indicated by the arrow) will retract the several shells, thereby opening the circuit in various places, and retensioning the spring 25 for use at the next successive period.

I claim:

30 1. An automobile signal of the class described comprising a plurality of shell members having external and internal flanges formed at their ends and adapted to tele-

scope one within the other, the largest shell being adapted to be anchored to the automobile-body, the smallest shell having a casing and a pair of convex lenses and a filament lamp secured thereto, a plurality of telescoping tube members secured to the largest and smallest shell member and adapted to telescope in unison with the shell members, an expansion coil spring retained in the chamber formed by the shell and tube members and adapted to yieldably keep the shells in extended position, means for releasably telescoping the shells one within the other, and means for energizing the filament lamp.

2. An automobile signal of the class described comprising a plurality of shell members adapted to telescope one within the other, a similar series of tubes adapted to telescope into each other and mounted outside of the said shell members, a spring adapted to urge the shells into extended 55 position, external and internal flanges formed to the ends of the said shell members, a pair of bolts secured to each of the said flanges, current carrying wires connecting said bolts, bolt heads in one shell flange adapted to contact with the bolt heads located on the adjacent flange, means for extending the tubes, and means for releasably retracting the same.

In witness whereof I affix my signature.
ADOLF BUTTER.
